UNITED STATES PATENT OFFICE.

ISAAC GORDON, OF NEW YORK, N. Y.

GAS WATER HEATER.

Application filed January 9, 1924. Serial No. 685,272.

To all whom it may concern:

Be it known that I, ISAAC GORDON, a citizen of the United States, and a resident of the city and State of New York, have invented certain new and useful Improvements in a Gas Water Heater, of which the following is a full, clear, and exact description.

The invention relates to a Bunsen style gas water heater and cooker, which is adapted to operate with a single or double lead burner in any type of water heater, or with any type of gas range, gas and coal combination, gas furnace heater or general water heater.

One of the objects of the invention is to provide a device of this character which will provide an adequate quantity of hot water for general purposes while the burner is being used for cooking, baking, etc., thereby not only adding to the usefulness of a range and saving the space and expense of a separate water heater, but also greatly reducing the consumption of gas.

Another object of the invention is to provide a water heater of this character so constructed that it in no way interferes with the direct application of the burner heat to the cooking vessel. On the contrary the construction of the water heater is such that it really assists in applying the heat to the cooking vessel and reduces the loss of heat by radiation.

Still other objects of the invention are to provide a burner and water heater so constructed that the heat of the burner is intensified against the water pipes or other style of water heater; so constructed that the diffusing of the heat from the water heating member will be prevented; so constructed as to eliminate the escape of carbon monoxide or other poisonous gases and also so constructed that the cooking, baking and heating may all be accomplished in a most sanitary manner.

Further objects of my invention will be apparent from the following detailed description when taken in connection with the accompanying drawings; in which,

Figure 1 is a front elevation of the casing detached from the range.

Figure 2 is a vertical sectional view through the casing, water heater, and burner.

Figure 3 is a plan view of the complete

device detached from the gas range, furnace, or the like.

Figure 4 is a perspective view of a double lead gas burner employed with my water heater.

Figure 5 is a perspective view of a single lead gas burner employed with my water heater.

Figure 6 is a perspective of a portion of a range with my water heater mounted in place therein; and

Figure 7 is a vertical sectional view of a modified form of water heater.

Referring to the drawings more in detail, particularly to Figure 5, numeral 1 indicates a single lead burner having an annular flange member at its lower end; the flange member being provided with two rows of holes, referred to by numeral 2, and arranged to direct the flame vertically against two coils of a water heater disposed directly over the holes. The upper portion of the burner is provided with a single circular series of holes 3 adapted to project the flame, at an angle of substantially 45° to the vertical, against the water heater. Also at the top of the burner are two cross-arms having holes 4 adapted to project the flame vertically. The burner is lined with asbestos between the upper and lower series of holes, as indicated by numeral 5. The burner which I have just described, and which is illustrated in Figure 5, has only a single lead 6, and hence it is necessary to employ the entire burner whether or not the full amount of heat is necessary.

In Figure 4 I have illustrated a double lead burner referred to generally by numeral 7. The construction is identical, except that there are two leads, 8, 8; and one of these leads furnishes gas solely to the holes in the cross-arms 4, while the other lead furnishes gas to the lower and upper series of holes, 2 and 3. By this arrangement it is possible to employ only the gas jets from the holes 4; or if preferred, only the gas jets from 2 and 3; or by opening both leads all the jets may be employed. The jets from 4 need only be employed when cooking alone is desired, or when fast cooking and water heating is desired; for the jets from the holes 2 and 3 will be sufficient for ordinary purposes.

A water coil, indicated generally by numeral 9, is mounted over either type of burner.

In Figures 2 I have shown the coil mounted over the double lead burner 7, such as illustrated in Figure 4. The particular coil employed is of very material importance.

- 5 By reference to Figure 2 it will be seen that the bottom of the coil is double; as indicated by numeral 10, and that one of these coils is arranged directly over each of the two circular rows of holes 2. The heating capacity is thus greatly increased for there are 10 two lower coils and there is a circular row of jets applied directly to each of the coils. The remainder of the water heater consists of single coils, and all of the coils are 15 slightly spaced to permit the flames to pass between the coils. At the top of the water heater each succeeding coil is of less diameter than the one below it, as clearly shown in Figure 2, and by this arrangement the 20 heat from the burner is prevented from being diffused, and also the flames from the upper holes 3 are caused to act more directly on the coil; and to assist in this direct action of the flames on the coil, the holes 3 are arranged at 45° to the vertical. 25

Water is carried from the tank (not shown) to the bottom of the coil by the pipe 11, and the pipe 12 carries the heated water from the top of the coil to the tank.

- 30 The burner and water heater are placed in a metallic cylindrical casing 13, provided with a door 14; and the interior of the casing is lined with asbestos, as indicated by numeral 15. To prevent any escape of carbon gases, vent holes 16 are provided in the top of the casing, and these may be connected to the range flues. The casing 13 is provided with hangers 17, and the casing with the burner and water heater arranged in 35 40 it is bolted to the inside part of the range, up against the cooking top thereof by means of the hangers.

In Figure 7 I have shown a modified form of water heater. This form of water heater is indicated by numeral 18, and it will be seen that it is of a general cylindrical shape with the upper portion thereof curved inwardly, so that it is of substantially the same shape as the coil water heater. The walls of the heater 18 are hollow, as indicated by numeral 19, and a pipe 20 supplies the water to the bottom of the heater, while pipe 21 carries off the heated water. It will be understood that the water heater 18 may be substituted for the coil water heater, if desired.

It is believed that the construction and operation of the device will be clearly understood from the foregoing description. The 55 particular shape of the coil not only results in a very rapid heating of the water but also prevents the diffusing of the heat; and by the use of an asbestos lining for the burner and casing, there is very little loss 60 65 of heat by radiation from the interior of

the burner or the exterior of the casing. Further, the construction of the water heater is such that it does not in any way interfere with the direct application of the flames from the holes 4 to the cooking utensil. 70 Further, by the use of a double lead burner there is a saving of fuel, for it is only necessary to use the jets 4 when there is cooking alone to be done, or the jets 2 and 3 only when there is to be ordinary cooking and 75 water heating; and jets 2, 3, and 4 only when there is to be rapid cooking and water heating.

The water heater may be in the form of a coil, or in any other form, such as the 80 cylindrical member 18 having its upper portion curved inwardly, as illustrated in Fig. 7; and it is therefore to be understood that the term "coil" used in the claims is intended to cover such an equivalent structure 85 as that illustrated in Fig. 7.

The present invention constitutes an improvement on my invention in water heaters disclosed in patent #1,474,931, granted to me November 20, 1923. 90

In accordance with the patent statutes, I have described what I now believe to be the best embodiment of the invention, but I do not wish to be understood thereby as limiting the scope of the invention, as many changes and modifications may be made without departing from the spirit of the invention; all such I aim to include in the scope of the appended claims: 95

Having fully described the invention, 100 what I claim as new and desire to secure by Letters Patent is:

1. A heating system including a burner having an upper and a lower series of jet holes, a water coil surrounding the burner and arranged directly over the lower series of holes, the upper portion of the coil being curved inwardly, the top of the coil having an opening therein so that flames from the upper series of jet holes may be applied vertically and directly to a cooking utensil adapted to be arranged thereover. 110

2. A heating system including a burner having a lower series of jet holes and two upper series of jet holes, a water coil adapted to be arranged directly over the lower series of jet holes, the upper portion of the coil being curved inwardly, one of the upper series of jet holes adapted to project the flames at an angle to the vertical and directly against the inwardly curved portion of the water coil, the other series of upper jet holes adapted to project the flame vertically and directly against a cooking utensil adapted to be arranged thereover. 120

3. A heating system including a burner having a lower series of jet holes and two upper series of jet holes, a water coil surrounding the burner and arranged directly over the lower series of jet holes, one of the 130

upper series of jet holes adapted to project the flame directly on the water coil, and the other upper series of jet holes adapted to project the flame vertically and directly on 5 a cooking utensil adapted to be arranged thereover.

4. A heating system including a burner having a lower series of jet holes and two upper series of jet holes, a water coil surrounding the burner and arranged directly over the lower series of jet holes, one of the upper series of jet holes adapted to project the flame directly on the water coil, the other upper series of jet holes adapted to project 10 the flame vertically and directly on a cooking utensil adapted to be arranged thereover, a separate gas lead for one of the upper series of jet holes, and another gas lead common to the other upper series of jet holes 15 and the bottom series of jet holes.

5. A heating system including a burner having an upper series of jet holes, and two series of lower jet holes, a water coil surrounding the burner, said water coil comprising a double coil at the bottom thereof 20 and a single coil throughout the body there-

of, each of said two lower coils arranged directly over one of the lower series of jet holes.

6. A heating system including a casing 30 and means for attaching the casing in a range or the like and up against the cooking top of the range, said casing having an asbestos lining, a burner having an upper and a lower series of jet holes mounted in 35 the casing, and a water coil also mounted in the casing and arranged directly over the lower series of holes.

7. The combination of a gas range or the like and a combined cooker and water 40 heater, said combined cooker and heater comprising a casing and means for attaching the casing in the range up against the cooking top thereof, a water coil arranged within the casing, and a burner arranged within 45 the water coil, said burner having an upper and a lower series of jet holes, the lower series of jet holes adapted to project the flame directly on the water coil, and the upper series of jet holes adapted to project the 50 flame directly on a cooking utensil.

ISAAC GORDON.
